UNITED STATES PATENT OFFICE.

DIEDRICH SCHULTE, OF PITTSBURG, KANSAS, ASSIGNOR OF ONE-HALF TO
ROBERT VOETH, OF SAME PLACE.

HOG-CHOLERA REMEDY.

SPECIFICATION forming part of Letters Patent No. 314,545, dated March 24, 1885.

Application filed July 18, 1884. (No specimens.)

To all whom it may concern:

Be it known that I, DIEDRICH SCHULTE, of Pittsburg, in the county of Crawford and State of Kansas, have invented a new and useful Improvement in Hog-Cholera Remedies, which improvement is fully set forth in the following specification.

My invention consists of a composition for the prevention and cure of cholera in hogs, and at the same time acts as an antidote against diseases common to hogs; and it consists of the following ingredients, combined in the following proportions: tartaric acid, one table-spoonful; asafetida, one table-spoonful; sulphur, one table-spoonful; black antimony, one table-spoonful; sulphate of iron, two table-spoonfuls; arsenic, three and one-half drams; tar, eighteen fluid ounces; linseed-oil, eight fluid ounces. These are thoroughly mixed together and designed to be the proportion for one quart of the preparation.

In the use of the remedy as described is found a speedy and effectual cure for cholera in hogs if used before the vital parts are involved beyond the reach of any aid, and it will not only purify the blood, but also effectually expel all poison from the system, and also aid and invigorate digestion.

The directions for using are as follows: dose, one table-spoonful of the remedy mixed with bran-mash given once a day for two days for cholera; dose, one-half the above once a month for prevention of cholera.

I am aware that heretofore a hog-cholera medicine has been compounded of arsenic, 35 podophyllum, poke-root, flowers of sulphur, saltpeter, sulphate of copper, sulphate of iron, antimony, stramonium-seeds, and asafetida, and do not claim such a medicine or compound. 40

What I claim is—

The herein-described composition, designed as a preventive and remedy for hog-cholera, consisting of tartaric acid, asafetida, sulphur, black antimony, arsenic, tar, and linseed-oil, 45 as and for the purposes substantially as herein set forth.

In testimony that I claim the foregoing I have hereunto set my hand, this 11th day of July, 1884, in the presence of witnesses.

DIEDRICH SCHULTE.
